UNITED STATES PATENT OFFICE

169,406

CLOTHESLINE SUPPORT

Thaddeus T. Zajac, Chicago, Ill.

Application September 16, 1952, Serial No. 21,483

Term of patent 7 years

(Cl. D49—1)

To all whom it may concern:

Be it known that I, Thaddeus T. Zajac, a citizen of the United States and a resident of Chicago, in the county of Cook and State of Illinois, have invented a new, original, and ornamental Design for a Clothesline Support, of which the following is a specification, reference being had to the accompanying drawing, forming part thereof;

The dominant features of my design reside in those portions shown in full lines.

I claim:

The ornamental design for a clothesline support as shown and described.

THADDEUS T. ZAJAC.
